UNITED STATES PATENT OFFICE.

JOSEPH JOACHIM REIFGRABER, OF ST. LOUIS, MISSOURI.

AUTOMATIC FIREARM.

1,418,021.

Specification of Letters Patent. Patented May 30, 1922.

Application filed June 8, 1920. Serial No. 387,929.

To all whom it may concern:

Be it known that I, JOSEPH JOACHIM REIFGRABER, a citizen of the United States, and a resident of St. Louis, in the State of Missouri, have invented certain new and useful Improvements in Automatic Firearms, of which the following is a specification.

My invention relates to improvements in automatic firearms, and it consists in the 10 constructions, combinations and arrangements herein described and claimed.

One of the foremost objects of my invention is to provide a one-hand automatic pistol which, as the term implies, is capable of 15 being relieved so that the operator may continue shooting in case of a "misfire" or "jam," "jam," and not requiring the use of the other hand to aid this function.

A further object of the invention is to 20 provide an automatic pistol which is inherently safe by virtue of the construction and operation of certain elements of which it consists in part, such means as the ordinary "safety" devices which require manipulation 25 by the other hand, being totally eliminated.

A further object of the invention is to provide an automatic pistol which embodies a normally locked breech block, but is so arranged that the breech block is unlocked by 30 virtue of the pressure of a fractional part of the gas following the discharge of a bullet.

Other objects and advantages will appear 35 in the following specification, reference being had to the accompanying drawings, in which:—

Figure 1 is a side elevation of the improved automatic pistol.

Figure 2 is a longitudinal section thereof, illustrating a bullet in the firing position 40 and the other parts of the mechanism in the normal positions.

Figure 3 is a similar sectional view illustrating the position of the hammer at the instant it is about to be released by the trigger 45 arm upon pulling the trigger, to fire the bullet.

Figure 4 is a similar sectional view illustrating the parts in the positions they assume after the bullet has been discharged,

50 Figure 5 is a horizontal section taken substantially on the line 5—5 of Figure 2,

Figure 6 is a vertical section taken on the line 6—6 of Figure 2,

Figure 7 is a detail sectional view of the top casing of the pistol, 55

Figure 8 is a detail sectional view of the breech block, and

Figure 9 is a detail sectional view of the gun frame.

This invention is an improvement on my 60 prior patent for automatic firearms granted July 27, 1909, No. 929,491, and also my prior Patents Nos. 729,413, granted May 26, 1903, and 834,753, granted October 30, 1906. The construction of the present firearm 65 has been greatly simplified and it is thought not out of place to outline a brief sketch of the purposes and advantages thereof before proceeding with the description.

Weapons of this type are ordinarily 70 equipped with various kinds of safety devices which require initial manipulation before they can be fired. As the reader will presently discover, this automatic pistol has no such devices, nor in fact does it require 75 them, the operation of unlocking the breech block being performed by the expansion of the gas after a bullet is discharged, against a portion of the breech block which performs the unlocking operation. 80

All of the necessary operations are carried out by the hand which holds the gun, the aid of the other hand not being required under any circumstance. In the event of a "misfire" or "jam," the operator needs only 85 to press down on the rear exposed end of the breech block and pull the trigger, whereupon the defective bullet will be discharged at the side and the shooting may be proceeded with as in the ordinary course. In a word, the 90 operation of the automatic pistol may be described as merely the pulling of the trigger, everything else taking care of itself in the proper order of events. With this brief outline in mind the reader's attention is now 95 directed to the general construction of the automatic pistol.

The gun frame comprises the barrel 1 which has a suitably rifled bore 2 with a shallow recess 3 at the rear and a gas vent 4 100 near the muzzle at the front. The trigger recess 5 opens into the cartridge clip cham-

ber 6 which in turn is embodied in the handle 7 of the pistol.

At the rear of the handle there is a bore 8 which houses the main spring 9 and plunger 10, both of which are parts of the breech block operating mechanism. A portion of the upper part of the gun frame is machined at 11 to provide a track on which the breech block rides. The upper surface 12 of the 10 fore part of the barrel inclines upwardly toward the rear, providing an abutment 13 at the rear, and a lock shoulder 14 at the front for the breech block 15, the breech block having a cooperating locking shoulder 15 16 which normally engages the gun frame shoulder 14 when the parts are in the initial position illustrated in Figure 2. At this time the shoulder 17 rests on the abutment 13, the return movement of the breech block 20 being limited by such engagement and all looseness of the breech block on the gun frame being further prevented by the careful fitting of the breech block on the fore part of the barrel.

25 The hammer bore 18 communicates with a smaller axial opening 19 at the front, through which the firing pin 20 of the hammer 21 projects upon pulling the trigger 22 to fire the cartridge C. In addition to the 30 shoulders 16 and 17 already mentioned, the breech block has intermediate and rear lock shoulders 23 and 24.

At one side of the hammer bore 18 there is a recess 25 (Fig. 8) in which the finger 35 26 of the breech-closing lever 27 works. It is through the agency of this lever, actuated by the main spring 9 and plunger 10, that the breech block 15 is returned to the forward or initial position after the firing 40 of a cartridge. A flange 28 on each side of the breech block 15 aids in accurately locating the breech block on the fore part of the barrel when the former is in the initial position, this flange 28 being cut out at 29 45 to coincide with the ejector opening 30 in the top casing 31, when the breech block is in the rearmost position illustrated in Figure 4. This top casing is pivoted to the gun frame at 32 at the front and at the rear has 50 an aperture 33 with a branch 34 to cooperate with the locking pin 35.

This pin is suitably mounted on the gun frame. When the exposed fingerpiece 36 is turned down so that the flat part 37 coincides with the branch 35, it is obvious that the top casing 31 may readily be swung up on its pivot 32 so as to gain access to the mechanism on the inside. On the contrary, when the fingerpiece 36 is swung up toward 55 the left as in Figure 1, the flat part is moved out of coincidence with the branch 34 so that the top casing may not be swung up. It therefore remains in the locked position on the gun frame. The casing has an abutment

38 with which the intermediate and rear shoulders 23 and 24 of the breech block successively engage. Normally, the rear shoulder 24 engages the abutment 38 when the breech block is in the forward or locked position and after the discharge of the cartridge C, at which time the lock shoulders 14, 16 are disengaged, the intermediate shoulder 23 engages the abutment 38 as in Figure 4.

The trigger 22 consists of two main parts: 75 the trigger itself, and the trigger arm 39 which is pivoted to the trigger at 40. The trigger is pivoted on the gun frame at 41 and has a bore which houses the spring 42, the spring pressing on the heel 43 of the 80 trigger arm, for the purpose of maintaining the engagement of the upper end with the hammer 21. The trigger arm is suitably shaped to straddle or embrace the cartridge clip 44 in the recess 6. The upper end of 85 the spring 42 engages the lip 45 on the gun frame.

The hammer 21, mentioned above, is hollow at 46 to partially contain the hammer spring 47 which rests against the back plug 90 48 in the bore 18. The back plug includes 49 which keeps the spring centralized in the bore. One side of the hammer is cut away at 50 so as to make room for the finger 26 of the breech-closing lever 27 95 (Fig. 6).

The lug 51 of the hammer 21 is engaged by the upper claw 52 of the trigger arm 39 when the hammer and breech block are in the normal or forward positions, at which 100 time the lower claw 53 on the same upper end of the arm 39, is clear of the heel 54 of the breech-closing lever 27. But if the rear exposed end of the breech block 15 is pressed down with the thumb of the hand which 105 holds the firearm, the lower claw 53 of the trigger arm 39 is thrust into engagement with the heel 54 of the breech-closing lever 27, it being observed in Figure 2 that the 110 claw 53 is directly above the heel 54.

Of course the breech block is unlocked by thus pressing down on the rear end. If the trigger 22 is now pulled, the breech closing lever 27 is carried rearwardly, conveying the breech block with it thereby extracting 115 and ejecting a defective shell from the firearm. The foregoing operation is intended to be carried out only in the event that a defective shell has moved up into firing position.

When the position in Figure 2 is assumed, the firing pin 20 rests but lightly on the primer of the cartridge, the trigger 22 and trigger arm 39 being in precisely the proper position to enable the upper claw 52 to engage the lug 51 of the hammer 21 and thus restrain the hammer from moving farther forward under the tension of the spring 47.

It is also to be observed that there is then a slight space between the shoulder 50 on the hammer and the rear edge of the lever 27.

This lever is pivoted at 55 on the gun frame and carries a roller 56 which affords an anti-friction engagement with the upper end of the plunger 10.

An extractor of any approved type, may be employed in connection with the breech block mechanism. For the purpose of illustration, a conventional form of extractor 57 is shown attached to the breech block in Figure 5. The free end of the extractor engages the rim of the cartridge C and pulls the empty shell out of the recess 3 in the barrel, on the rearward movement of the breech block. When the empty shell C reaches the opening 30 in the top casing 31, the firing pin 20 of the hammer 21 acts as 20 the ejector, in the manner described under the operation.

When the breech block uncovers the magazine recess 6, a fresh cartridge is moved up into the breech of the pistol in position to 25 be forced into the recess 3 on the return or forward movement of the breech block. Although not shown, the reader will understand that there is a spring inside of the cartridge magazine 44 which forces the cartridges upwardly. The functions of the various parts described above will be more readily understood in connection with the following operation: Normally, the breech block 15 is in the position illustrated in Figure 2, the shoulder 16 being supported on the shoulder 14 of the gun frame, the rear shoulder 24 and abutment 38 being in engagement, and the hammer 21 being in the position at which the firing pin 20 is 30 retracted in the aperture 19, but resting lightly on the cartridge primer.

The operator now pulls the trigger 22. This causes the trigger arm 39 to move rearwardly a sufficient distance with the trigger, the upper claw 52 being in engagement with the lug 51, causing the hammer 21 to move backwardly in the bore 18 against the tension of the hammer spring 47, and when the position in Figure 3 has been reached, 45 the upper claw slips from the lug 51. The hammer 21 is then released and the firing pin 20 caused to strike the primer and explode the cartridge C. Up to this time, the breech block 15 remains immovable in respect to the gun frame.

But as soon as the bullet reaches the vent 4, and a fractional part of the gas behind it, expands against the front portion of the breech block in advance of the shoulder 16, 50 the breech block is lifted from engagement with the shoulder 14 while the rear shoulder 24 is lowered from engagement with the abutment 38, thereafter moving rearwardly 55 until the position in Figure 4 is reached. It

is the pressure of gas through the empty shell against the middle of the breech block that forces the breech block back into the position mentioned in connection with Figure 4.

The arrangement is such that on the rearward stroke of the trigger arm 39, (as long as the breech block 15 is locked) the lower claw 53 avoids the heel 54 of the breech closing lever 27 but at the same time, the upper claw 52 engages the lug 51 of the hammer. 75 After the trigger 22 has reached the rearward position, the trigger arm 39 assumes a different position by reason of its uppermost curvature, the upper claw 52 then being unable to engage the lug 51 of the hammer 80 as can be plainly seen both in Figures 3 and 4.

As stated above, the old shell is extracted from the recess 3 by the extractor 57 on the rearward movement of the breech block 15, and when the opening 30 is reached, is ejected 85 by the firing pin of the hammer. This action can readily be understood by bearing in mind that so long as the breech block is locked in its forward position, there is a space between the shoulder 50 and the closing lever 27; but the moment the breech is unlocked, that space is taken up by the consequent but slight downward movement of the breech block from its locking abutment.

This downward movement of the breech 95 block necessarily causes the finger 26 to move slightly farther into the recess behind the shoulder 50 so that the firing pin is withdrawn within the aperture 19 and remains in this position until the breech block 100 reaches the rearmost position in Figure 4. At that time the tip of the finger is very low in the recess behind the shoulder 50 and provides room enough for the hammer spring 47 to force the hammer 21 forwardly 105 so that the firing pin projects beyond the aperture 19 as clearly shown in Figure 4. When the pin has thus been projected, the empty shell ejecting action takes place, the extractor hook 57 acting as a pivot on which 110 the shell is swung out.

Now when the breech block moves forwardly again through the action of the spring 9 on the breech closing lever 27, which lever operates against the hammer 115 shoulder 50 to gradually retract the hammer and hold it in that position during the entire forward or return movement. It may now be assumed that the breech is closed but not locked. The locking of the breech occurs when it moves slightly upwardly to bring the rear shoulder 24 into engagement with the abutment 38, this by virtue of the spring 9 acting on the finger 26, whereafter the upper claw 52 reengages the lug 51 and 125 lightly supports the firing pin 20 on the primer of the cartridge.

While the construction and arrangement

of the improved automatic pistol as herein described and claimed, is that of a generally preferred form, obviously modifications and changes may be made without departing 5 from the spirit of the invention or the scope of the claims.

I claim:—

1. A firearm, including a body with a portion having an abutment, and a barrel 10 with a lock shoulder; and a breech block with rear and front shoulders normally in engagement with the abutment and lock shoulder respectively, to lock the breech block in the initial position, and an intermediate shoulder engageable with the abutment to limit the recoil of the breech block when a portion of the block adjacent the front shoulder is lifted from the lock shoulder by gas pressure.
2. A firearm, including a gun frame, with a reciprocable breech block moved to a recoiled position from an initially locked position on the frame, from which it is released by gas pressure, the breech block having a groove; tensionable means for returning the breech block to the initially locked position, including a frame-housed spring with a plunger; and actuating means including a breech closing-lever movable with the block 25 by engagement of a portion thereof with said groove, and having an anti-friction member bearing on the plunger.
3. A firearm, including a barrel with a lock shoulder and an abutment; and a breech block with a recessed portion defining shoulders corresponding to and engaging said abutment and lock shoulder respectively when the breech block is initially seated on that portion of the barrel.
4. A firearm, including an inclined-top barrel with a lock shoulder and an abutment, and a top casing with a rear abutment; and a breech block, recessed to define shoulders corresponding to and engaging with the abutment and lock shoulder respectively when the breech block is in the initially locked position on that portion of the barrel, a rear shoulder on the block engaging the rear casing abutment through the then 50 inclined position of the breech block.
5. The combination of a barrel, a breech block initially seated and locked in position on the barrel, with a hammer bore having a spring-pressed hammer; and a trigger with means for retracting and releasing the hammer independently of the breech block to discharge a bullet, a portion of the gas behind the bullet releasing the breech block from the locked position and subsequently 55 moving it, together with the hammer, to a recoiled position.
6. A firearm, including a breech block with a bore and a lateral communicating groove, a spring-pressed hammer in the bore, with a lateral cut-away portion pro-

viding a shoulder; and a breech closing lever with a finger facing said cut-away portion and entering said groove, and engaging said shoulder to retract the hammer in the bore against the tension of the spring when the breech block moves from a recoiled to a forward position.

7. A firearm, including a hammer, an associated breech closing lever with a heel, and a trigger with a trigger arm having an upper claw initially engaging a portion of the hammer to move the latter to a firing position when the trigger is pressed and thereupon releasing the hammer, and a lower claw engageable by said heel on a return movement of said lever to restore the trigger to an initial position at which the upper claw and hammer portion re-engage.

8. A firearm, including a barrel, with a muzzle-piece having an upper portion removed to leave a lock shoulder; and a breech block fitting on the barrel, with a front piece offset to leave a shoulder to engage the lock shoulder and secure the breech block in the initial position.

9. The combination in a firearm, of a hammer, with a firing pin and a lug; a trigger, with a trigger-arm normally engaging the lug to prevent more than the lightest engagement of the firing pin with the primer of a cartridge, and a curve in the arm causing disengagement thereof from the lug after the hammer is predeterminedly retracted by pulling the trigger, to permit the hammer to snap forwardly unobstructedly against the primer.

10. A firearm, comprising a gun frame and top casing, with a cartridge magazine and lateral ejector opening; a breech block normally in locked engagement with the top casing, having its rear end exposed for thumb-pressure and movable to an unlocked position in respect to the top casing; and a trigger with a trigger arm in normally operation connection with a hammer carried by the breech block, to move the latter backwardly by pulling the trigger and cause the ejection of a defective cartridge out of said opening.

11. A firearm, including a barrel with a lock shoulder at the front, a casing abutment, and a breech block with a lock shoulder to normally engage the lock shoulder at the front, a rear lock shoulder normally engaging the casing abutment, and an intermediate lock shoulder adapted to subsequently engage the casing abutment.

12. A firearm, including a barrel with a lock shoulder at the front, a casing abutment, a breech block with a lock shoulder at the front, a rear lock shoulder normally engaging the casing abutment and an intermediate lock shoulder adapted to subsequently engage the casing abutment; and instrumen-

abilities for separating the front lock shoulders by gas pressure following the discharge of a bullet, also separating the rear lock shoulder from the abutment to enable the intermediate lock shoulder to engage said abutment.

13. A firearm, including a barrel with a chamber having a front lock shoulder, a casing abutment, a breech block operating in the chamber and having a bore having a front axial opening, including a front lock shoulder normally engaging that of the barrel, a rear lock shoulder normally engaging

the casing abutment, and an intermediate lock shoulder in normal disengagement; 15 and a hollow hammer actuated by a spring in the breech block bore, with a firing pin retracted from the axial opening; and means holding the hammer retracted but releasing it to discharge a cartridge, a portion of the 20 escaping gas operating to separate the front lock shoulders and the rear lock shoulder from the casing abutment with which the intermediate lock shoulder subsequently engages.

JOSEPH JOACHIM REIFGRABER.
